(57) **CLAIM**

The ornamental design for an outdoor multifunctional emergency disaster mitigation bluetooth radio, as shown and described.

DESCRIPTION

FIG. 1 is a top, front and right side perspective view of an outdoor multifunctional emergency disaster mitigation bluetooth radio, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front and right side perspective view thereof, shown in condition of use with the lid opened and the handle in an extended configuration; and,

FIG. 9 is a rear and left side perspective view thereof.

The broken lines depict portions of the outdoor multifunctional emergency disaster mitigation bluetooth radio in which the design is embodied that form no part of the claimed design.
